LOUIS VICTOR PIGUET, OF NEW YORK, N. Y.

Letters Patent No. 78,823, dated May 26, 1868.

IMPROVEMENT IN WATCHES.

The Schedule referred to in these Letters Patent and making part of the same.

TO ALL WHOM IT MAY CONCERN:

Be it known that I, LOUIS VICTOR PIGUET, of the city, county, and State of New York, have invented a new and improved Winding and Setting-Apparatus for Watches; and I do hereby declare that the following is a full, clear, and exact description thereof, which will enable others skilled in the art to make and use the same, reference being had to the accompanying drawings, forming part of this specification, in which—

Figure 1 represents a face view of my invention on an enlarged scale.

Figure 2 is a side view, partly in section, the plane of section being indicated by the line x x , fig. 1.

Similar letters of reference indicate corresponding parts.

This invention relates to a new pendant-winder and setter, and consists in the use of a key, which fits through the pendant, and which has, at its inner end, a toothed crown-wheel, which gears into a pinion that is fitted in the movement.

The latter pinion gears into two other toothed pinions, of which one is mounted on a swinging bar and gears into the barrel-ratchet.

The other is mounted on the oscillating shifting-bar and can, by a push-piece, be brought to gear into the common pinion, whence the setting-apparatus is completed.

A represents the case or "centre" of the watch. B is its pendant, through which a pin, C, is fitted, so as to reach into the inside of the watch.

The outer end of this pin is provided with a milled handle, a, while on its inner end a pinion, b, is formed, which has the teeth on its end, as on a crown-wheel, and as shown in figs. 1 and 2.

The ordinary pusher for opening the case on hunting-case watches by pressure can be applied and fitted through the key C in the ordinary manner.

The pinion b meshes into the teeth of a gear-wheel, D, which is fitted in the "movement" of the watch around a screw, c, and between a lever, E, and a cap, d, as shown.

The screw c is prevented from turning out by another screw, e. The lever E swings or turns on the pin c, and carries a pinion, F, which meshes into the barrel-ratchet G, as shown.

A spring, f, presses upon one end of the lever or plate E, so as to throw the wheels F and G into gear with each other.

When the pinion D is turned in the direction of the arrow 1, in fig. 1, the teeth on the wheel, besides turning the wheel F, have the tendency to throw the same toward the centre of the watch; thereby the pinion F is, so to say, hemmed in between the wheels D and G, and transmits motion from one to the other.

When the wheel D is turned in the direction opposite to that which is indicated by the arrow 1, the teeth on D move the wheel F toward the rim of the watch-case, and thereby the plate E is turned so as to be forced against the spring f. Thereby the wheel F is thrown out of the wheel G, and thus, when the wheel D is turned in the direction last mentioned, it will not wind up, nor will it strain the teeth of the pinion G and thereby tend to break the main-spring, while, when D is turned in the direction of the arrow 1, the watch will be wound up.

It will be observed that the teeth on the wheels D, F, and G, are not cut, as usual, on cog-wheels, but that they are made conical.

This makes their construction easier and cheaper, but they can, if desired, be made as usual.

H is the cannon-wheel, and I the hour-wheel, both of which are, of course, toothed. The former meshes into the teeth of a cog-wheel or minute-wheel, J, which is of exactly the same size and has the same number of teeth as the minute-wheel.

The minute-wheel turns on a pin, g, which is fixed so as that it cannot be moved sidewise. A small pin, h, is formed on the pin g, and meshes into the hour-wheel I.

Between the minute-wheel and the wheel D is a pinion, K, which is mounted on a spring-shifter plate, L, that is operated by a push-knob, k, from the outside of the watch.

By pushing in the knob k the wheel K is brought against the wheels D and J, and communication is thus established between the key C and the cannon and hour-wheels, and the hands can be set by turning the key C.

On the plate L or knob h is formed a projection, i, which fits over the end of the plate E, and which when the knob h is pushed in, turns the plate E on its pin, e, so as to throw the pinions F and G out of gear. Thus, when the setting-apparatus is in gear, the winding-apparatus is out of gear, and *vice versa*.

The teeth of the pinion b being cut on the end, the "movement" can be removed from or inserted in the case without trouble as easy as an ordinary movement, and the pinion b need not be made of a very exact size, as long as it is large enough to reach the level of the wheel D.

The necessity of making and adjusting the case with that great accuracy and precision, which is necessary on ordinary pendant-winders, is thus overcome.

By the arrangement of the enlarged cannon-pinion and hour-wheel, the hands are steadied, and more power, as well as security of motion, is provided.

Having thus described my invention, what I claim as new, and desire to secure by Letters Patent, is—

1. The combination of the knob h, spring-plate L, and lever E, operating as herein described, whereby the pressure upon the knob h throws the setting-mechanism in gear and the winding-mechanism out of gear, substantially as herein shown and described.

2. The arrangement, in the watch-case, of the key C, having pinion b, wheel D, spring-lever E, wheels F G, shifter-plate L, knob h, pinions K, J, g, H, and I, all constructed and operating as described, for the purpose specified.

3. The arrangement of the key C, wheel D, spring-lever E, pivoted upon the pin e of said wheel, and bearing the wheel F, and the wheel G, all operating as described, in such a manner that by turning the key C in one direction the wheel F is bound between the wheels D G to wind the watch, and turning the key in the opposite direction releases the wheel F and prevents the winding of the watch, as herein shown and described.

4. The key C, having the crown-gear wheel b, in combination with the wheels D F G, spring-lever E, spring-arm L, pinion K, wheels J H g h I, as herein described, whereby the watch is wound and set by the same key, independently of each other, as herein shown and described.

L. V. PIGUET.
